DESIGN FOR A STORE

George W. Clapp, New York, N. Y.

Application December 22, 1936, Serial No. 66,690

Term of patent 14 years

To all whom it may concern:

Be it known that I, George W. Clapp, a citizen of the United States, residing at New York, in the county of New York and State of New York, have invented a new, original, and ornamental Design for a Store, of which the following is a specification, reference being had to the accompanying drawing forming a part thereof.

In the drawing:

bodying the present invention, and illustrating one end and the front in normal open condition.

Figure 3 is a perspective of the front of the store with the parts thereof in closed position.

I claim:

The ornamental design for a store as shown and described.

GEORGE W. CLAPP.
